(57) **CLAIM**

The ornamental design for a solar music lamp, as shown and described.

DESCRIPTION

FIG. 1 is a front, bottom perspective view of a solar music lamp showing my new design.

FIG. 2 is a rear, top perspective view of the solar music lamp.

FIG. 3 is a front view of the solar music lamp.

FIG. 4 is a rear view of the solar music lamp.

FIG. 5 is a left view of the solar music lamp.

FIG. 6 is a right view of the solar music lamp.

FIG. 7 is a top view of the solar music lamp; and,

FIG. 8 is a bottom view of the solar music lamp.

The shading is not a feature of the design but is utilized to illustrate the surface contours of the solar music lamp design in the drawings.

The broken lines in the drawings depict portions of the solar music lamp that form no part of the claimed design.
